UNITED STATES PATENT OFFICE.

ROBERT FLEETWOOD NICHOLS, OF OAKLAND, CALIFORNIA.

CASEMENT-WINDOW.

1,143,059.

Specification of Letters Patent. Patented June 15, 1915.

Application filed January 8, 1913, Serial No. 740,870. Renewed August 24, 1914. Serial No. 858,342.

To all whom it may concern:

Be it known that I, ROBERT FLEETWOOD NICHOLS, a citizen of the United States, and a resident of Oakland, in the county of Alameda and State of California, have invented new and useful Improvements in Casement-
5 Windows, of which the following is a full and exact description.

I am cognizant of the fact that casement
10 windows are in use that swing inward; such casements are very satisfactory in fair weather for cleaning the outer fronts of the casements, for full ventilation, etc. In stormy weather they are a source of annoy-
15 ance on account of rain or snow being driven through the outer fronts of the casements. Heretofore architects, builders and others have been unable to so design and construct casement windows as to make them storm
20 proof from the outside, and the casements, singly or collectively, readily swing inward so as to permit the use of outside screens for ventilation and other purposes.

The object of the invention is to overcome
25 this difficulty and so construct a casement window that when the casements are in their normal position in the casement frame they will be proof against storms from the outside and readily, singly or collectively, swing
30 inward to clean their outer panes, for ventilation and other purposes, also permit the use of outside screens to prevent the ingress of flies, mosquitos, etc.

The invention consists in the novel con-
35 struction and combination of the several parts, as will be hereinafter fully set forth and pointed out in the claims.

Reference is to be had to the accompany-
40 ing drawings, forming a part of this speci-
fication in which similar characters of ref-
erence indicate corresponding parts in all
the figures.

Figure 1 is a front elevation of a casement window frame, having the improvements
45 applied thereto, and illustrating the casements, the closing bar, and turn buttons to secure the closing bar to the casements. Fig.
2 is a horizontal cross section through H,
Fig. 1, and illustrates the left hand casement
50 jamb, rabbets formed in the jambs and
grooves formed in the rabbets; also illus-
trates the hanging stiles of the casements,
grooves formed in the hanging stiles con-
55 nnecting with like grooves formed in the rab-
bets of the casement jambs; grooves formed
in the inner edges of the hanging stiles, and

hinges to connect the casements with the case-
ment jambs. Fig. 3 is a detailed horizontal
cross section through G, Fig. 1, and illus-
trates the inner and outer fronts of the meet-
ing stiles of the casements B, B, the form of
60 the rabbets and lips in their inner and outer
edges, the grooves formed in the outer lip
and rabbet of the meeting stiles. Also it
illustrates the rabbet and lip in the inner
65 fronts of the meeting stiles, as being of
greater depth outward, than the rabbet and
lip in the outer fronts of the meeting stiles
are inward. Fig. 4 is a detailed perpendic-
ular cross section through C, Fig. 1. This
70 section shows the window sill, E, the closing
bar D, the lower section of the right hand stile
F of the left hand casement B, and an inner
section of the lower rail of a casement; also
illustrates the manner of forming the win-
75 dow sill, E, the closing bar, D, the perpen-
dicular groove in the lip of the right hand
meeting stile F of the left hand casement B,
the rabbets formed in the inner lower edges
of the lower rails of the casements. It fur-
80 ther illustrates the outer and lower lip of
the closing bar D, as overlapping the upper
and inner lip of the window sill E and the
outer lip in the lower edges of the casement
85 rails as overlapping the upper and inner lip
of the closing bar D.

A, represents a casement window frame,
B, B, the casements, F, F, the casement stiles,
E, the window sill and D, the closing bar,
the casement frame A being provided with
90 rabbeted jambs L, Fig. 2, a window sill E
and the usual finish for casement windows.
The rabbets in the casement jambs L, form re-
cesses to receive the casements B, B. Hinges
8 carry the casements B, B. Perpendicular
95 grooves, 6, are formed in the inner front
edges of the rabbets of the casement jambs
L. The window sill E on its inner upper
edge 2 is provided with a lip 7 Fig. 4; in the
outer front of the lip 7, a longitudinal semi-
circular groove 10 is formed. In the lower
outer front of the lip 7 a similar longitudi-
100 nal semicircular groove 13 is formed to con-
nect with and form a part of the outward
and downward slope of the window sill E.
The closing bar D on its inner front and
lower edge is provided with a rabbet I to
105 form a lip 14, in the lower and outer front
of the closing bar D, to connect with the lip
7 and form a closure with the window sill E.
110 In the inner front of the lip 14, a longitudi-
nal semicircular groove 11 is formed to con-

nect with a like groove 10, formed in the outer front of the lip 7 of the window sill E to prevent water passing up by capillary attraction, through the lip 7 of the window sill E and the lip 14 of the closing bar D. In the lower and inner edge of the lip 14 of the closing bar D a longitudinal semicircular groove 12 is formed to connect with the upper part of the semicircular groove 13 formed in the lower and outer front of the lip 7 of the window sill E to form a circular groove, so that water driven under the lip 14 of the closing bar D would be repelled. The upper and outer front of the closing bar D is cut away to form an inner lip 15 and the upper edge 16 of the lip 15 is sloped downward and outward. In the lower and outer front of the lip 15, a longitudinal semicircular groove 18 is formed. Intersecting with the groove 18 at an acute angle 21 the outer front of the closing bar D is sloped downward to a point 22. The closing bar D is connected with the window sill E by means of hinges 9 secured to the upper and inner edge 2 of the window sill E and the lower and inner edge 1 of the closing bar D. The object of sloping the closing bar D at an acute angle 21, is that when the closing bar D is turned inward by means of the hinges 9, it will pass clear of the lower edges of the lips 19 of the casements B, B. The casements may then be singly or collectively swung inward and replaced in the casement frame A; the closing bar D can then be returned to its normal position in the casement frame A and form a closure with the window sill E and the casements B, B, illustrated by solid lines in Fig. 4.

The hanging stiles F, F, of the casements B, B, are connected with the casement jambs L, by means of hinges 8 to carry the casements B, B. In the outer fronts of the hanging stiles F, F, Fig. 2, within the rabbets of the casement jambs L, perpendicular semicircular grooves 4, are formed to connect with like grooves 6 formed in the inner fronts of the rabbets of the casement jambs to form channels or outlets to pass off water driven between the hanging stiles F, F, and the casement jambs L. As an additional protection from storms, grooves 3, 3 are formed in the inner edges of the hanging stiles F, F.

Rabbets 17, 17 are made in the lower inner edges of the casements B, B, to form lips 19 in the lower edges of the outer fronts of the casements B, B. The rabbets 17 are sloped downward and outward to conform to the slope 16 in the upper edge of the lip 15 of the closing bar D. When the closing bar D is in its normal position in the casement frame A, it is held in that position by means of turn buttons 28, 28, secured to the inner front of the lower rails of the casements B, B.

In the inner fronts of the casements B, B, the right hand meeting stile F of the left

hand casement B is provided with a rabbet 23 and the left hand meeting stile F of the right hand casement B, is provided with a lip 24. In the outer fronts of the casements B, B, the left hand meeting stile F, of the right hand casement B, is provided with a rabbet 25, and the right hand meeting stile F of the left hand casement B, is provided with a lip 26. In the edges of the rabbet 25 and the lip 26 perpendicular semicircular grooves 27 are formed to pass off water that might be driven between the rabbet 25 and the lip 26 of the meeting stiles of the casements B, B.

It will be noted that the rabbet 23 and the lip 24 in the inner fronts of the meeting stiles are of greater depth outward than the rabbet 25 and the lip 26 in the outer fronts of the meeting stiles are inward. The object of this is, that the lip 15 of the closing bar D, and the lip 19 in the lower edges of the casements B, B, form a longitudinal closure within the lines of the perpendicular rabbet 25, and the lip 26, in the edges of the meeting stiles in the outer fronts of the casements B, B, so that any water driven between the casement stiles and the casement jambs or between the rabbet 25 and the lip 26 of the meeting stiles, would pass down the perpendicular grooves in the casement stiles and casement jambs to the slope 21 in the outer front of the closing bar D, off the closing bar D to the window sill E and out of the casement frame A.

It can readily be seen that the perpendicular grooves 6, 6, formed in the inner front edges of the casement jambs L, the grooves 3, 3, in the inner edges of the hanging stiles, the grooves 4, 4, in the outer fronts of the hanging stiles, the grooves 27, 27, in the outer rabbet 25 and the outer lip 26 of the meeting stiles of the casements B, B, the intersection of the lip 15 of the closing bar D with the lips 19 of the lower rails of the casements B, B, the intersection of the lip 7 of the window sill E with the lower lip 14 of the closing bar D, the longitudinal grooves 10 and 13 in the lip 7 of the window sill E and the like grooves 11 and 12 in the lower lip 14 of the closing bar D, make the casement window impervious to rain or snow and storm proof.

When it is desired to open the casements B, B, the turn buttons 28, 28 are turned from the perpendicular to the horizontal position shown in Fig. 1. The casements B, B, can then be swung inward, the lower rails of the casements B, B, turning the closing bar D, from the perpendicular to the horizontal position illustrated by the dotted lines in Fig. 4. It is plainly to be seen that when the closing bar D, is in the horizontal position the casements B, B, will pass freely over the outer front of the closing bar D inward, and as freely pass over it when being replaced

in the casement frame A. When the casements B, B, are in their normal positions in the casement frame A, the closing bar D is then returned from the horizontal to its 5 normal perpendicular position in the casement frame A, the upper lip 15 of the closing bar D forming a closure with the lips 19, 19 in the lower rails of the casements B, B, the lower lip 14 of the closing bar D 10 forming a closure with the lip 7 of the window sill E. The turn buttons 28, 28 are returned from the horizontal to the perpendicular position securing the closing bar D firmly to the casements B, B, so that the 15 casements B, B, and the closing bar D can not be removed until the turn buttons 28, 28 are again returned to the horizontal position. I desire it to be understood that other devices may be employed in place of the 20 turn buttons without departing from the spirit of the invention.

I am aware that rabbets are well known devices used for many purposes. I therefore do not make any claim to them as rabbets, but the novel construction and particular division of the rabbets, so necessary to the accomplishment of the object of the invention.

I claim:

30 1. The combination with a casement window frame and casements therefor, as described; a movable closing bar to connect said casements with the casement frame; said closing bar having in its inner and 35 lower edge, a longitudinal rabbet, adapted to connect with the inner and upper edge of the lip of the window-sill; a longitudinal lip in its outer and lower edge, a groove in the inner front of the lip, said lip adapted 40 to overlap the outer front of the lip in the window-sill and make a closure with the casement frame; a longitudinal lip in its inner and upper edge, a longitudinal groove in the outer and lower front of the lip; said 45 lip adapted to connect with the longitudinal rabbet and lips in the lower edges of the casements, making a closure with the casements and the window-sill, at an acute angle in its outer front, the closing bar being 50 sloped downward from the lower outer front of the lip, in its inner and upper edge; to permit of its being automatically turned to a horizontal position when the casements

are drawn inward; means for connecting the closing bar with the window-sill and means 55 for securing it to the casements, all substantially as shown and described.

2. In combination with a casement sill and casement, a strip hingedly mounted on a horizontal axis between said casement and 60 casement sill and engaging with a rabbet groove in the rear edge of the lower rail of the casement so that the casement overhangs and laps the upper part of said strip, the rear lower corner of the strip being recessed 65 to receive, overhang and lap an upwardly projecting rear portion of the sill.

3. In combination with a casement sill and casement therefor, said casement sill formed at its rear edge with an upwardly 70 projecting portion extending for the full length thereof, said casement formed with a rabbet in the rear edge of the lower rail thereof and a strip mounted to pivot on a horizontal axis between said casement and 75 casement sill and adapted for engagement at one edge with said rabbet groove and at another edge for overhanging and lapsing the forward edge of said upwardly projecting portion on said casement sill. 80

4. In combination with a casement sill and casement, a strip hinged to said sill and engaging with a rabbet groove in the rear edge of the lower rail of the casement so that the casement overhangs and laps the 85 upper part of said strip, the rear lower corner of the strip being recessed to receive, overhang and lap an upwardly projecting rear portion of the sill.

5. In combination with a casement sill 90 and casement, a strip hinged to said sill and engaging with a rabbet groove in the rear edge of the lower rail of the casement so that the casement overhangs and laps the upper part of said strip, the rear lower corner 95 of the strip being recessed to receive, overhang and lap an upwardly projecting rear portion of the sill, the relative vertical and horizontal dimensions being such, and the hinge axis being so located, that the 100 swinging of the casement inwardly will automatically tilt said strip inwardly.

ROBERT FLEETWOOD NICHOLS.
